United States Patent Office

Des. 229,189
Patented Nov. 13, 1973

229,189

LOUDSPEAKER CABINET

Seth E. Lover, 12752 Adrian Circle,
Garden Grove, Calif. 92640

Filed Oct. 20, 1971, Ser. No. 191,136

Term of patent 14 years

Int. Cl. D14—03

U.S. Cl. D26—14 G

FIG. 1.

FIG. 2

FIG. 3

FIG. 4

FIG. 5.

FIG. 6.

FIG. 1 is a front isometric view of a loudspeaker cabinet showing my new design;

FIG. 2 is a top plan view thereof;

FIG. 3 is a rear isometric view;

FIG. 4 is a front elevation;

FIG. 5 is a cross section taken on line 5—5 of FIG. 4; and

FIG. 6 is a cross section taken on line 6—6 of FIG. 4.

I claim:

The ornamental design for a loudspeaker cabinet, substantially as shown and described.
